Specification for Design.

Patented Jan. 5, 1915.

Application filed November 17, 1914. Serial No. 872,664. Term of patent 3½ years.

To all whom it may concern:

Be it known that I, JOHN MERRY, a subject of the King of Great Britain, residing in New York city, in the county of New York and State of New York, have invented a new, original, and ornamental Design for a Rug of Carpet Sizes, of which the following is a specification, reference being had to the accompanying drawing, forming part thereof.

The drawing illustrates a portion of a rug showing my new design.

I claim:

The ornamental design for a rug, substantially as shown.

JOHN MERRY.
